UNITED STATES PATENT OFFICE.

BENJAMIN W. TUCKER, OF SOUTH ORANGE, NEW JERSEY, ASSIGNOR TO CORONA TYPE-WRITER COMPANY, INC., OF GROTON, NEW YORK, A CORPORATION OF NEW YORK.

TYPE-WRITING MACHINE.

1,247,348.

Specification of Letters Patent. Patented Nov. 20, 1917.

Continuation in part of application Serial No. 820,244, filed February 21, 1914. This application filed March 11, 1916. Serial No. 88,539.

To all whom it may concern:

Be it known that I, BENJAMIN W. TUCKER, a citizen of the United States, and a resident of South Orange, county of Essex, 5 and State of New Jersey, have invented certain new and useful Improvements in Type-Writing Machines, of which the following is a full, clear, and exact description.

This invention relates more particularly

- 10 to a front strike or other visible typewriting machine and is a continuation in part of my application Serial No. 820,244, filed February 21, 1914, which has matured into Patent 1,222,497, dated April 10, 1917.
- 15 One of the principal objects of the invention is to provide a typewriting machine in which key-operated levers of a keyboard may be mounted upon one frame part, member or section of the main supporting frame, 20 and the platen carriage, type-bars and other parts mounted upon another frame part or member of the main frame, and a separable positive connection made between the key-operated levers and the type-bars or other 25 parts operated by the keys of the keyboard in order that the frame part supporting the keys may be folded from a normal operative position to a more compact one to reduce the lengthwise dimension of the machine.
- 30 Another object of the invention is to provide simple and efficient means forming a positive direct connection between the type-bars and key-operated levers of a universal or standard keyboard, and means whereby 35 the connection between the type-bars and key-operated levers may be simultaneously moved to place the same in an inoperative position with respect to the key-operated levers whereby the key-operated levers may 40 be moved from a normal operative position to an abnormal and more compact position.

Other objects of the invention are to provide simple and efficient means whereby all the parts including the universal bar, the 45 shift means and the type-bars may be operated by links having a separable but positive connection with foldable key-operated levers; to provide simple means whereby the key-operated levers may be suitably mounted 50 and guided on a foldable section or part of the main frame; and to provide mechanism which may be mounted in a skeleton form of frame which is adapted to be fixed within a carrying case, or in which the frame

may be constructed and arranged to be used 55 separately or be placed in a separate carrying case, or in which the mechanism may be mounted in a support or frame which may in itself form a carrying case and adapted when closed to inclose entirely the mechanism and parts of the typewriter to adapt 60 the same to be readily transported from place to place.

A further object of the invention is to provide a simple, effective and substantially direct connection between the keyboard and type-bars which is simple in construction and may be readily made and assembled.

With these and other objects in view, the invention will be hereinafter more particularly described with reference to the accompanying drawings, which form a part of this application, and will then be pointed out in the claims at the end of the description.

In the drawings, Figure 1 is a plan view, partly broken away and partly in section, of one form of machine embodying the invention.

Fig. 2 is a longitudinal section, partly 80 broken away and partly in elevation, the section being taken on the line II—II of Fig. 1.

Fig. 3 is a view somewhat similar to Fig. 2 except that the keyboard has been moved from a normal operative position to a more 85 compact one in which the keyboard overhangs the type-bars and the space bar located near the platen of the platen carriage.

Fig. 4 is a plan view, Fig. 5 an end view, and Fig. 6 a vertical section showing in detail one of the key-operated levers.

Fig. 7 is a detail perspective view of a part of the guiding means for the upwardly extending arms of the key-operated levers.

Fig. 8 is a vertical section, partly in elevation and partly broken away, of a part of the case shift mechanism.

Fig. 9 is an end view, partly broken away, of the mechanism shown in Fig. 8.

Fig. 10 is a sectional view of the type-bar 100 operating means showing the position of the parts when a key has been depressed to move the type to the printing point.

Fig. 11 is a fragmentary perspective view of part of the means for separating the connection between the type-bars and key-operated levers; and

Fig. 12 is a fragmentary longitudinal sec-

- tion showing how a positive separable connection may be made between the key-operated levers and the links without having to move the outer ends of the links for separation to permit folding of said key-operated levers. The main frame 10 comprises a main frame part, section or member 11 and a keyboard frame part, member or section 12. The main frame part 11 comprises side walls 13 and a rear connecting wall 14 and at the front and rear corners of said part are angular brackets 15 for the usual or any preferred form of rubber feet. The frame part 11 has its side walls 13 at the front portion extending inwardly a short distance as at 16, and secured to said inwardly extending portion 16 are brackets or bearings 17. Upwardly extending arms or parts 18 of the keyboard frame part 12 are pivotally held by screws 19 or otherwise to the brackets 17 so that said frame part may be moved relatively to the main member or part 11 from a normal operative position to an overhanging position with relation to the type-bars in order that a substantially uniform box-like package may be provided when the machine is not in use. This keyboard or frame part 12 has side walls 20 substantially triangular in form which are connected together at their front portions by a transversely extending bar 21. While a particular form of frame is shown and means whereby one member is hinged to the other member to fold relatively thereto, it will be understood that the frame may be variously constructed and either or both members may be provided with suitable rubber or other feet 22, as is usual in typewriting machines.
- A plurality of supporting rods 23, 24 and 25 are supported between the side walls 20 of the frame member 12. On the rod 23 are pivotally held a number of key-operated levers 26, and on the rod 24 a number of key-operated levers 27 are pivotally arranged, while on the rod 25 are a number of key-operated levers 28. Each key-operated lever is substantially bell-crank in form and has a vertically arranged arm 29 and a horizontally arranged arm 30, at the outer end of which is a finger key 31. The key-operated levers are thus arranged in groups or banks, and the arms of each group or bank are of different lengths from the other banks, the vertical arms and horizontal arms of each group being of substantially the same length so that a substantially uniform touch is secured. The key-operated levers 26 and 27 are restored to their normal position by means of springs 32 and the lowermost group of key-operated levers 28 are restored to their normal position by means of springs 33. Each key-operated lever has an angular portion, as 34, Fig. 4, in order to provide a substantial bearing to permit the key-operated levers to be self-spacing along their fulcrum or supporting rods and each key-lever has its vertical arm guided in a slot 35 in a comb plate or guide 36 located above the key-operated levers and supported by the keyboard frame part or member 12. The key-operated levers are thus supported by the frame part 12 and are adapted to partake of the folding movement thereof. The key-operated levers are each provided with forked or bifurcated upper ends 37 which are adapted to receive the outer ends of links 38. Each link 38 is connected at its inner end to a lug 39 of a type-bar 40, the latter being pivoted at 41 to a segment or a hanger as preferred and is adapted when the link is moved outwardly to force the outer end of the type-bar upwardly and rearward against the platen 42, the latter being mounted on a platen carriage 43 which is adapted to travel transversely of the main member 11 under the control of suitable escapement mechanism as is usual in this character of machine. The type-bars each carry a plurality of type according to whether a single or double case shift is provided and at their outer ends rest upon a cushion 44 mounted upon a metal rest 45 of any suitable kind. The links 38 at their outer ends are each provided with a boss or collar 46 and are slidably held to move forwardly and rearwardly in a plate or bar 47. This bar 47 extends transversely of the machine between the side walls of the main frame member, and said bar is formed integral with or secured to rearwardly extending arms 48 which are pivoted at 49 by screws or otherwise to the side walls of the main member 11. The bar 47 has apertures one for each link, and on each link is a second collar 50, and interposed between said collar 50 and the bar is a spring 51 tending normally to restore each link 38 and its co-operating type-bar to their normal position. The arms 48 and bar 47 form a guide and supporting frame for the links and one of the arms is provided with an opening 52 in which is adapted to work an eccentric or eccentrically arranged disk 53. The disk 53 is adapted to be moved by a handle 54 located on the outside of the frame and said handle is limited in either of its positions by pins or other stops 55. The links as already described are normally seated in the bifurcated ends of the key-operated levers so as to be separable therefrom, and in the normal operative position each link is positively connected to its co-operating key-operated lever. If the lever 54 of the eccentric or disk 53 is moved upwardly, the disk 53 will cause the arms 48 and bar 47 to be also moved in the same direction, and this will carry the links therewith and separate said links from the key-operated levers to permit the frame member 130

or part 12 with the key-operated levers to move to the position shown in Fig. 3. After the eccentric lever 54 is moved to the position shown in Fig. 2 and the keyboard frame part or member 12 is also in the position shown in Fig. 2, the links will then be located in the slots or bifurcated ends of the key-operated levers so that on the depression of any key a link will be operated and its operating type-bar moved on its pivot to force the type against the platen. By this means a simple and effective separable direct and positive connection is made between the key-operated levers and type-bars adapting the keyboard frame part to be moved relative to the main frame part so as to place the keyboard in a more compact position and reduce the dimension of the machine.

The invention is shown as embodying a platen shift, but it will be understood that a type segment shift may be employed in connection with a machine of this kind, and so far as the case shift is concerned it forms no part of the present invention. As shown in the drawings, the ribbon spools and such other parts which coöperate with the platen carriage are mounted to partake of the shift movement of the carriage and that may be true of the escapement dogs in substantially the same manner as the well-known form of the Corona typewriter. As shown and as is common in the Corona typewriter a rocking frame 56 is provided which is adapted during its rocking movement to operate the escapement dogs and also the ribbon vibrating and feed mechanism. The rocking frame is pivotally held to a transversely extending rod 57 located at the lower portion of the main frame part 11 and at its upper end is slotted to receive a transversely extending rod 58. The rod 58 is connected to the vertical arms of bell-crank levers 59. These bell-crank levers are pivotally held to the upright arms 60 of a universal bar 61. The universal bar 61 is guided in arms 62 which have slotted front ends and are pivoted at their rear ends at 63 to brackets held to the rear wall of the main frame part 11. The universal bar is adapted to be moved by a projecting part or extension 64 on each type-bar at each movement thereof so that during the printing operation as usual the universal bar will also be operated to control the letter feed movement and the operation of the ribbon mechanism.

A link 65 connects the arm 62 to an arm 66. This arm 66 is held to a stud or shaft 67 and to this stud or shaft is held an upright arm 68 to which is connected a link 69. The link 69 extends forwardly and is constructed substantially the same as the links 38. The link 69 is provided with collars 69^a and 69^b and is guided in apertures in the transversely extending bar 47 and is normally held in one position by means of

a spring 69^c similar to the springs 51 so that said link 69 partakes of the separable movement of the bar 47. The link 69 is connected to a substantially bell-crank spacing lever 70. There may be two levers 70 if desired or only one and said levers are mounted on the lower transversely extending rod 25. Projecting from the forward end of said rod 25 are two arms 71 which are connected together by the space bar 72 so that on the depression of the space bar the link 69 will be operated and this through the arms 68, 66 and link 65 will move the arm 62 and cause a downward movement of the universal bar to permit letter feed movement of the carriage without operating the printing instrumentalities.

As a means for shifting the platen carriage, various means may be employed. As shown two bell-crank levers 73 and 74 are located on opposite sides of the machine. These levers are held on a transversely extending rod 75. The levers 74 are secured to the rod 75 to move in unison while the levers 73 are connected by a tubular sleeve 76 also to move in unison but independently of the levers 74. The inner ends of the horizontal arms of the levers 73 and 74 are hook-shaped to engage under the rod 57, and each horizontal arm is provided with a screw or adjustable stop 77. The stops 77 of one set of arms are longer than the stops of the other set of arms and said stops are adapted to engage an angular transversely extending bar 78 so that when the bell-crank levers are moved the sets of arms will shift the rod 57 together with the rocking frame and the platen carriage and bed in a vertical direction to relatively different distances according to which set of bell-crank levers is operated, the purpose of having the levers on opposite sides of the machine being to provide a uniform movement and to form a positive stop at opposite sides of the machine. The bell-crank levers 73 and 74 at one side of the machine are each connected by a link 79 and these links 79 are guided in the bar 47 in a similar manner to the links 38 and 69. Each link 79 has a collar 80, Figs. 1 and 8, and between each collar 80 and the inner face 115 of the transversely extending bar 47 is a spring 81 tending normally to force the links and shift levers 73 and 74 to their normal position. At the outer end of each link 79 is a second collar 82 which is adapted to be engaged by the bifurcated or forked arm of either one of the shift levers 83 and 84, said shift levers being mounted as shown on the supporting rod 24 of the key-operated levers and each of said levers being adapted to be locked in either one of its adjusted positions or both locked against movement by means of a single lever 85. The lever 85 is pivoted at 86 to one side of the machine and has its lower end adapted to enter

cesses in either or both of the platen shift levers as is common in the Corona typewriter. If either of the shift levers is moved it will operate one of the sets of bell-crank 73 and 74 and this will move the platen carriage and other parts a distance corresponding to which shift key is operated as already described.

In Fig. 12 the type-bars 87 are connected to links 88. These links 88 are guided at their outer ends in a stationary bar 89, there being an opening in said bar for each link. Each type-bar and its coöperating link are restored to their normal operative position by a spring 90, said spring being interposed between the guide bar 89 at one end and a collar 91 located on said link at the other end of said spring. Each link is provided with a collar 92 at its outer end and adapted to engage said collar is the slotted end of the arm 93 of a key-operated lever 94. There are a number of key-operated levers 94 arranged in banks as already described and each key-operated lever may be guided by a slotted plate 95, each key-operated lever being restored to its normal position by a spring 96 or otherwise. As in the other form described the key-operated levers form a part of the keyboard and are mounted upon a keyboard or frame part 97. The frame part 97 is foldable upwardly and rearwardly in a manner already described and carries the key-operated levers 94 therewith. The frame part 97 is pivoted at 98 to the main part of the frame of the machine on which the type-bars 87 are mounted. This pivot or hinge 88 is so positioned with relation to the connection between the links 88 and the arms 93 of the key-operated levers that the folding of the frame part 97 will disconnect the arms 93 from the links without requiring the bar 89 to be moved and when the keyboard with the frame part 97 is restored to its normal operative position the links and key-operated levers are again brought into engagement. By this means a positive separable connection is made between the key-operated levers and the links and the eccentric disconnecting means is dispensed with.

From the foregoing it will be evident that simple and efficient means is provided whereby a separable connection is made between key-operated levers and type-bars as well as other parts of the operative mechanisms; that simple means is provided whereby a number of links may be simultaneously released from a number of key-operated levers or be placed in position to be in operative relation thereto to adapt the machine during the separation of the links from said levers to be folded or otherwise moved to a compact position and as soon as restored to a normal operative position placed in operative connection with said links; that said

machine may have its frame variously constructed to adapt the mechanism disclosed therein to be employed as a part of a typewriter in which its cubical dimensions may be materially reduced when not in use; and that said mechanism is adapted to be mounted in a skeleton frame to be placed in another frame or case, or the said mechanism may be suitably mounted in a frame which may be used independently of a carrying case or be placed in a separate carrying case when it is desired to transport the machine.

Having thus described my invention, I claim as new and desire to secure by Letters Patent:—

1. In a typewriting machine, the combination of a main frame part, type-bars mounted upon said frame part, a platen carriage movable transversely of said frame part, a keyboard frame part hinged to the main frame part to move upwardly and rearwardly thereon, key-operated levers mounted upon said keyboard frame part, and separable means forming a direct and positively interlocking connection between each type-bar and one of the key-operated levers to be folded with the keyboard frame part.

2. In a visible typewriting machine, the combination of a main frame part, type-bars mounted upon said frame part, a platen carriage movable transversely of said frame part, a keyboard frame part held to the main frame part to move from a normal operative position to an abnormal compact one, key-operated levers forming a part of a universal keyboard mounted upon said keyboard frame part, and separable means forming a direct positively interlocking connection between each type-bar and one of the key-operated levers to adapt the key-operated levers to partake of the compact movement of the keyboard frame part.

3. In a typewriting machine, the combination of a main frame part, type-bars mounted upon said frame part, a carriage movable transversely of said frame part, a keyboard frame part held to the main frame part to move from a normal operative position to an abnormal compact one, key-operated levers mounted upon said keyboard frame part, and a link for each type-bar forming a separable means and a direct positive connection between each type-bar and one of the key-operated levers to adapt the key-operated levers to partake of the compact movement of the keyboard frame part.

4. In a visible typewriting machine, the combination of a main frame having two relatively movable parts adapted in one position to be extended and in another position to be compact, type-bars mounted on one of the frame parts, key-operated levers mounted on another frame part, and sep-

arable means forming an interlocking connection between each type-bar and one of the key-operated levers.

5. In a typewriting machine, the combination of a main frame having two parts hinged together to fold and unfold and in the normal unfolded position to be extended and when folded to be compact, a platen carriage movable on one frame part, type-bars movably held on the same frame part, key-operated levers mounted on another frame part and foldable therewith, and separable means forming an interlocking connection between each type-bar and one of the key-operated levers to adapt the key-operated levers to fold with the keyboard frame part.

6. In a typewriting machine, the combination of a main frame part, type-bars mounted on said frame part, a key-board frame part, key-operated levers mounted on said keyboard frame part and adapted with said frame part to be moved from a normal operative position to an abnormal compact one, type-bars mounted upon the main frame part, links forming a direct connection between the type-bars and the key-operated levers, there being one type-bar and one link for each key-operated lever, and means for moving the links to separate the same from the key-operated levers to adapt the key-operated levers to partake of the compact movement of the keyboard frame part.

35 7. In a visible typewriting machine, the combination of a main frame part, type-bars mounted on said frame part, a keyboard frame part pivotally held to the main frame part, key-operated levers mounted on said keyboard frame part and adapted with said frame part to be moved from a normal operative position to an abnormal compact one, type-bars mounted upon the main frame part, links forming a direct connection between the type-bars and the key-operated levers, there being one type-bar and one link for each key-operated lever, pivotally held supporting means for the ends of the links, and means for moving said supporting means to disconnect said links from the key-operated levers to adapt the key-operated levers to fold relatively to the type-bars.

8. In a typewriting machine, the combination of a main frame part, type-bars mounted on said frame part, a key-board frame part, key-operated levers mounted on said keyboard frame part and adapted with said frame part to be moved from a normal operative position to an abnormal compact one, type-bars mounted upon the main frame part, links also mounted on the main frame part and forming a direct connection between the type-bars and the key-operated levers, there being one type-bar and one link for each

key-operated lever, and means for separating the links from the key-operated levers to adapt the key-operated levers to fold relatively to the type-bars from a normal operative position to a more compact one.

9. In a typewriting machine, the combination of a main frame having a main frame part and a keyboard frame part, a platen carriage movable on the main frame part, type-bars carrying upwardly and rearwardly moving type also mounted on the main frame part, a link connected to each type-bar, a link-supporting frame pivotally held on said main frame part, means for moving said link-supporting frame, key-operated levers arranged in banks and mounted on the keyboard frame part each key-operated lever having a slotted upper end adapted to engage one of the links, a collar adapted to be engaged by one end of the key-operated lever to force the link in one direction, a second collar held to each link, a spring interposed between said latter collar and a part of the link-supporting frame tending normally to force the link and its type-bar to its normal position, and means for moving the link-supporting frame to simultaneously separate the links from the different key-operated levers to adapt the key-operated levers to be moved from a normal operative position with the keyboard frame part to an inoperative compact position relative to the platen carriage and the type-bars.

10. In a typewriting machine, the combination of a main frame part, a keyboard frame part, a platen carriage movable on the main frame part, type-bars carrying upwardly and rearwardly moving type also mounted on the main frame part, a link connected to each type-bar, a link supporting frame movably held on said main frame part, key-operated levers arranged in banks and mounted on the keyboard frame part, each key-operated lever having a slotted upper end adapted to engage one of the links, and means for moving the link-supporting frame to separate the links from the different key-operated levers to adapt the key-operated levers to be moved from a normal operative position with the keyboard frame part to an inoperative compact position relative to the platen carriage and the type-bars.

11. In a typewriting machine, the combination of a main frame part, a keyboard frame part, a platen carriage movable on the main frame part, type-bars also mounted on the main frame part, a link connected to each type, a link-supporting frame pivotally held on said main frame part, key-operated levers arranged in banks and mounted on the keyboard frame part, each key-operated lever having a slotted upper end adapted to engage one of the links, and a manually operated eccentric for moving the link-supporting frame to separate it from the differ-

- ent key-operated levers to adapt the key-operated levers to be moved from a normal operative position with the keyboard frame part to an inoperative compact position relative to the platen carriage and the type-bars.
12. In a typewriting machine, the combination of a main frame part, a keyboard frame part, a platen carriage movable on the main frame part, type-bars carrying upwardly and rearwardly moving type also mounted on the main frame part, a link connected to each type, a link-supporting frame pivotally held on said main frame part, key-operated levers arranged in banks and mounted on the keyboard frame part, each key-operated lever having its end adapted to engage one of the links, a spring tending normally to force the link and its type-bar to its normal position, and eccentric means for moving the link-supporting frame to separate the links from the different key-operated levers to adapt the key-operated levers to be moved from a normal operative position with the keyboard frame part to an inoperative compact position relative to the platen carriage and the type-bars.
13. In a typewriting machine, the combination of a main frame, a keyboard frame part held to the main frame and movable from a normal operative position to a more compact position, bell-crank levers pivotally supported on the keyboard frame part carrying keys at their outer ends and having forked upper ends, means engaging said levers to guide the same, type bars mounted in the main frame, and links operatively connected at one end with said type bars and adapted to be embraced by the forked ends of said key levers when the keyboard frame part is in operative position, said links being provided with abutments adapted to be engaged by the forked ends of the key levers to operate said links.
14. In a typewriting machine, the combination of a main frame, a keyboard frame part held to the main frame and movable from a normal operative position to a more compact position, bell-crank levers pivotally held to the keyboard frame part carrying keys at their outer ends and having forked upper ends, type bars mounted on the main frame, and links operatively connected at one end with said type bars and adapted to be embraced by the forked ends of said key levers when the keyboard frame part is in operative position, said links being provided with abutments adapted to be engaged by the forked ends of the key levers to operate the links.
15. In a typewriting machine, the combination of operative parts, a main frame part forming a support for said operative parts, links connected to said operative parts, a keyboard frame part movable relatively to said frame part, key-operated levers mounted upon said keyboard frame part, and direct separable connections between the key-operated levers and the said links.
16. In a typewriting machine, the combination of operative parts, a frame part forming a support for said operative parts, links connected to said operative parts, a keyboard frame part hinged to fold relatively to the said frame part, key-operated levers mounted upon said keyboard frame part, and links directly and separably connecting the key-operated levers and the said operative parts.
17. In a typewriting machine, the combination of operative parts, links connected to said operative parts, means normally forcing the links in one direction, a pivotally held frame forming a guide and support for one end of said links, an eccentric device adapted to move said link-supporting frame to carry the links simultaneously therewith, and foldable key-operated levers mounted upon the keyboard frame part and having a separable connection with said links.
18. In a typewriting machine, the combination of operative parts, links connected to said operative parts, springs normally forcing the links in one direction, a pivotally held frame forming a guide and support for one end of said links, a manually operated eccentric device adapted to move said link-supporting frame to carry the links simultaneously therewith, and foldable key-operated levers mounted upon the keyboard frame part and having a separable connection with said links.
19. In a typewriting machine, the combination of a main frame, a keyboard frame part held to the main frame and movable from a normal operative position to a more compact position, bell-crank levers pivotally supported on the keyboard frame part carrying keys at their outer ends and having forked upper ends, means engaging said levers to guide the same, type bars mounted in the main frame, links operatively connected at one end with said type bars and adapted to be embraced by the forked ends of said key levers when the keyboard frame part is in operative position, said links being provided with abutments adapted to be engaged by the forked ends of the key levers to operate said links, and means for shifting said links into and out of the forked ends of the key levers.
20. In a typewriting machine, the combination of a main frame, a keyboard frame part held to the main frame and movable from a normal operative position to a more compact position, bell-crank levers pivotally held to the keyboard frame part carrying keys at their outer ends and having forked upper ends, type bars mounted on the main frame, links operatively connected at one end with said type bars and adapted to be embraced by the forked ends of the key levers to operate the links.

- end with said type bars and adapted to be embraced by the forked ends of said key levers when the keyboard frame part is in operative position, said links being provided with abutments adapted to be engaged by the forked ends of the key levers to operate the links, and means for shifting said links into and out of the forked ends of the key levers.
- 10 21. In a typewriting machine, the combination of a main frame, type bars supported in the main frame, bell-crank levers arranged in groups and movable relatively to the type bars from a normal operative position to a more compact inoperative position, one arm of each of the levers supporting a key and the levers of the different groups being of different length and pivotally supported at points in different horizontal planes, and links connected at one end with the type bars and having separable connections at their opposite ends with said bell-crank levers at points in alignment transversely of the frame.
- 15 22. In a typewriting machine, the combination of a main frame, type bars supported in the main frame, links operatively connected at one end with the type bars, a keyboard frame part pivotally held to the main frame and foldable upwardly and rearwardly from a normal operative position to a more compact position, a plurality of groups of bell-crank levers pivotally mounted on the keyboard frame part and foldable therewith, the levers of the different groups being of relatively different lengths and carrying keys at one end and having separable connections at their opposite ends with said links, both arms of the levers being of substantially equal length.
- 20 23. In a typewriting machine, the combination of a main frame, type bars supported in the main frame, links operatively connected at one end with the type bars, a keyboard frame part pivotally held to the main frame and foldable upwardly and rearwardly from a normal operative position to a more compact position, and a plurality of groups of bell-crank levers pivotally held to the keyboard frame part on pivots arranged in different horizontal planes, said levers supporting keys at one end and having separable connections with said links at their opposite ends, both arms of the levers being of substantially equal length and the levers of the different groups being of relatively different lengths.
- 25 24. In a typewriting machine, the combination of a main frame, type bars mounted in the main frame, a keyboard frame part pivotally held to the main frame and foldable upwardly and rearwardly from a normal operative position to a more compact position, a plurality of groups of bell-crank levers of relatively different lengths pivotally mounted in the keyboard frame part and supporting keys in banks, and separable operating connections between said levers and the type bars to adapt the levers to fold with the keyboard frame part.
- 30 25. In a typewriting machine, the combination of a main frame, type bars mounted in the main frame, links connected at one end with the type bars, means held to the main frame for supporting the opposite ends of said links, a keyboard frame part held to the main frame and movable from a normal operative position to a more compact position, key-operated levers pivotally held intermediate their ends to the keyboard frame part, and means forming separable operating connections between said levers and links.
- 35 26. In a typewriting machine, the combination of a main frame, type bars mounted in the main frame, links connected at one end with the type bars, means held to the main frame for supporting the opposite ends of said links, a keyboard frame part held to the main frame and movable from a normal operative position to a more compact position, key-operated levers pivotally held intermediate their ends to the keyboard frame part, and coöperating means carried by said levers and said links forming positively interlocking separable operating connections between said levers and links to adapt said levers to actuate the type bars when in normal position and to move with the keyboard frame part to compact position.
- 40 27. This specification signed this ninth day of March, A. D. 1916.
BENJAMIN W. TUCKER.
